UNITED STATES PATENT OFFICE

NICHOLAS R. HAKIM, OF NEW YORK, N. Y.

DESIGN FOR A SHOE COVERING WITH CROSS-LACE ORNAMENTATION

Application filed January 7, 1932. Serial No. 42,398. Term of patent 3½ years.

To all whom it may concern:

Be it known that I, NICHOLAS R. HAKIM, citizen of the United States, and resident of New York, in the county of Kings and State of New York, have invented a new, original and ornamental Design for Shoe Covering with Cross-Lace Ornamentation, of which the following is a specification, reference being had to the accompanying drawings forming part thereof, in which—

Fig. 1 is a plan view of a shoe vamp showing my new design as applied thereto. However, it is contemplated to use the design on other parts of shoe uppers.

Fig. 2 is a fragmentary reverse view of Fig. 1 showing the opposite side of the design.

I claim:

The ornamental design for shoe covering with cross-lace ornamentation as shown and described.

Dated, December 24th, 1931.

NICHOLAS R. HAKIM.
